UNITED STATES PATENT OFFICE.

EDWARD HETT, OF NEW YORK, N. Y.

PRESS.

SPECIFICATION forming part of Letters Patent No. 662,863, dated November 27, 1900.

Application filed November 20, 1899. Serial No. 737,650. (No model.)

To all whom it may concern:

Be it known that I, EDWARD HETT, a citizen of the United States, and a resident of New York, (New Dorp,) in the county of Richmond 5 and State of New York, have invented certain new and useful Improvements in Presses, of which the following is a specification.

My invention relates to presses, and especially to means for supporting printing-forms 10 in presses. Its object is to provide improved means for supporting printing-forms in printing or transferring or other presses so arranged and adapted as to permit the insertion of printing-forms laterally directly into 15 working position in the press and to permit their removal laterally directly therefrom without the necessity of moving the printing-forms toward or away from the impression-surface after insertion into the press or before removal therefrom or of dismantling the 20 press; also, to provide means for holding the printing-form rigidly in place when in printing position to prevent the giving of such printing-forms when in such position; also, 25 to combine such supporting means for printing-forms with means for exerting pressure between the printing-form and the impression-surface; also, to combine such supporting means in a multicolor-press with suitable 30 guiding means, so as to permit not only the removal of the printing-forms from the press laterally directly from their working positions in the press, but also their insertion from the side of the press laterally directly 35 into their working positions in the press to bring the printing-forms into exact and co-operating relation with one another and with the impression-surface, so as to print in exact and accurate register with one another and, 40 to do this without experiment or further adjustment than the mere lateral insertion described herein.

It consists of the novel devices herein shown and described.

Heretofore in rotary presses, and particularly in multicolor-presses, to which my invention is peculiarly applicable, it has been necessary in order to place a printing-form in its working position in the press without 45 dismantling the press to move it over its supports into a position above its working position or one farther removed from the im-

pression-surface and then to lower or move it into its working position, and it has been necessary when removing a printing-form 55 from its working position in the press to raise it or move it away from the impression-surface out of its working position in order to clear its supports before it could be moved laterally out of the press. This movement 60 of the printing-form toward or away from the impression-surface after or before the lateral insertion or removal of the printing-form into or from the press either makes it necessary to leave an open space on the outside of the 65 printing-press, within which the inking-rollers or the damping-rollers cannot be placed, or makes it necessary, if the inking-rollers or damping-rollers are located in part or in whole in said space, to make them removable 70 therefrom when it is desired to remove or insert a printing-form, thus complicating the mechanism of this part of the press. In such presses the space within which the inking or damping rollers, or both, can be placed is thus 75 very much restricted and the mechanism of the press is rendered more complicated, less manageable, and more difficult to oversee and repair. By my invention I am enabled to move the printing-forms from the side of 80 the press laterally directly into working position and to remove them from working position directly and laterally out of the press without any movement toward or away from the impression-surface after or before the lateral insertion or removal of the printing-form and without any dismantling of the press. Accordingly the inking-rollers and mechanism and also the damping-rollers and mechanism, where the latter are used, can be 85 placed around the periphery of the printing-form at any desired position and may be arranged and mounted in any desired manner.

My improved device is of especial value in multicolor-presses where there are a plurality 95 of printing-forms, and particularly in multicolor lithographic presses.

In the drawings accompanying this specification and forming part hereof, and in which similar reference characters represent corresponding parts, I have shown my invention embodied in its preferred form in connection with a multicolor lithographic printing-press.

Referring now to the drawings, Figure 1 is an elevation of the preferred form of my improved support for printing-forms. Fig. 2 is a vertical section taken on the lines A A of Fig. 1 viewed as shown by the arrow. Fig. 3 is a plan of the parts shown in Fig. 1. Fig. 4 is a horizontal section taken on the lines B B, Fig. 1, viewed as shown by the arrow. Fig. 5 is a vertical section taken on the lines C C of Fig. 1 viewed as shown by the arrow. Fig. 6 is a side view of a multicolor lithographic printing-press, showing my improved support in its preferred form, as shown in Figs. 1 to 5, in position in such press. Fig. 7 is an elevation of a modified form of my improved support with a portion of the clamp cut away. Fig. 8 is a side elevation of the parts shown in Fig. 7. Fig. 9 is a horizontal section on the line E E of Fig. 7 viewed as shown by the arrow. Fig. 10 is a vertical section on the lines D D of Fig. 7 viewed as shown by the arrow. Fig. 11 is a horizontal section on the lines G G of Fig. 7 viewed as shown by the arrow. Fig. 12 is an elevation of a modified form of my improved support, and Fig. 13 is a vertical section of the same on the lines F F of Fig. 12 viewed as shown by the arrow.

Referring now to the preferred form or embodiment of my improved support for printing-forms, (shown in Figs. 1 to 5, inclusive, and shown in Fig. 6 in a six-color multicolor-press,) 1 is a printing-form which, as here shown, is a hollow or tubular cylinder having a shaft 2. Any suitable printing-form may be used in my improved device, it not being essential that the printing-form be hollow or cylindrical or have a continuous printing-surface. The printing-surface may, if desired, be a hollow shell-like tube, as shown at 3 in Figs. 2 and 13, mounted upon an interior form-support or mandrel 4, as shown in said figures, and removable from and replaceable upon the form-support. I preferably employ curved cylindrical printing-forms having a continuous printing-surface or having a surface adapted to be transformed into a printing-surface. The mandrel 4 may, if desired, be removable from and replaceable upon shaft 2. 5 is the impression-surface, which, as here shown, is an impression-drum around the periphery of which are circumferentially arranged a series of printing-forms 1, as shown in Fig. 6. Any suitable impression-surface, however, may be used. As shown in Fig. 1, the support for the printing-form consists of a frame 6, provided with two bearing-arms 7, the latter being adapted to be moved toward or away from each other by means presently to be described and adapted when brought together to form a bearing for the shaft of the printing-form. For this purpose the two bearing-arms have at their center each a semicylindrical opening 8. When the bearing-arms are brought together, these two semicylindrical openings form a cylindrical opening for the shaft 2 and its bushing

9. When the bearing-arms are separated sufficiently, they will clear the periphery of the printing-form 1, permitting the printing-form or its form-support, or both, to be moved in a lateral direction directly out from its working position in the press or permitting the same or another printing-form or its form-support to be inserted from the side of the press laterally and directly into working position in the press.

For the sake of conciseness and clearness the term "lateral movement" is used in this specification and in the claims to indicate a movement of the printing-form or its form-support from the side of the press inward parallel with the impression-surface or with the line of the axis of the printing-form or movement in the reverse direction. The term "working position" of the printing-form will be used in the specification and claims herein to indicate the regular position of the printing-form in the press either when the press is in operation or at rest, in the former case the printing-form being, of course, down upon the impression-surface in its printing position and when at rest being moved a slight distance away from the impression-surface. Both of these positions, however, are included in the term "working position."

Frame 6 is preferably supported upon pressure-bar 10. This pressure-bar is secured to the frame in the ordinary way by means of nuts 11 upon the screw-threaded upper end of pressure-bar 10, thus permitting a regulation of the pressure to suit. The pressure-bar and through it the frame 6 are moved up and down to bring the printing-form into printing position or to move it away from the impression-surface into its position of rest by any suitable means. As shown in Fig. 6, pressure-bars 10 are preferably moved from a common center, so that all will have the same movement. The particular means for moving the pressure-bars, however, form no part of the present invention and are not shown in detail and will not be further described.

Bearing-arms 7 may be moved toward or away from each other by any suitable means. As shown in Figs. 1 to 5, these means consist of two rods 12, screw-threaded, as shown, with the screw-threads upon each half of each rod running in the reverse direction. Nuts 13, forming part of bearing-arms 7 at the ends of each bearing-arm, surround the screw-threaded rods 12 and engage with said rods. Rods 12 are rotated, in the form shown in the drawings, by a gear-wheel 14 on each rod meshing with a large common gear-wheel 15, placed between gear-wheels 14 and mounted on the same shaft as worm-wheel 16. A worm 17 on shaft 18 meshes with worm-wheel 16 and is rotated by hand-wheel 19. Preferably the hand-wheel 19 and gear-wheel 15 and their connecting mechanism are mounted upon the framework of the press and do not move with frame 6. In order to permit gear-

wheels 14 to mesh at all times with gear 15, no matter what the position of frame 6, I make gear-wheel 15 very broad. This enables gear-wheels 14 as they rise and fall with frame 6 to slide in the teeth of gear-wheel 15 and always keep in mesh with it. By turning hand-wheel 19 rods 12 are rotated, thus causing bearing-arms 7 to separate from each other when hand-wheel 19 is turned in one direction and to approach each other when hand-wheel 19 is turned in the reverse direction.

By the use of the worm 17 worm-wheel 16 and bearing-arms 7 are locked in any position into which they are moved. Any suitable device may be employed for locking them in position; but I prefer to use a worm and worm-wheel, as described.

It will be noted that my said improved support for printing-form has in the form shown in Figs. 1 to 5 a portion—namely, the bearing-arms 7—removable from the path of the printing-form or its form-support when the latter is removed laterally from the press or is inserted from the side of the press into working position therein to permit the printing-form or its form-support to be inserted laterally directly into working position in the press or to be removed laterally directly therefrom. In my device it is accordingly unnecessary when a printing-form or its form-support is being removed from working position in the press to first raise it or move it away from the impression-surface in order to clear its supports and then to remove it laterally, and it is also unnecessary when a printing-form or its form-support is to be inserted into working position in the press to move it first laterally into a position above its working position in the press, but farther removed from the impression-surface than is its working position in order to clear the supports, and then to move it toward the impression-surface to bring it into working position. It will also be noted that the insertion and removal of printing-forms require no dismantling of the press or any part thereof; also, that by means of my improvement printing-forms can be moved out of working position in the press and they or other similar printing-forms can be moved into working position and be placed in exact predetermined position in the press without any empiric adjustment by simply moving the said removable portion of the support back to its original position.

My improved device above described furnishes means both for supporting the printing-form and for controlling the pressure between it and the impression-surface, while at the same time having a portion of said supporting and pressure means permanently secured to the said supporting and pressure means, but movable thereon, so as to be removable from the path of the printing-form as it is moved laterally and directly into or out of working position in the press. They

also furnish means for locking the support in its supporting position.

My improved support may be used at both ends or at one end only of the shaft of the printing-form. In practice it is necessary to use it only at one end, the other end being supported in any suitable manner by any suitable form of support.

It is important in a press, especially where heavy printing pressure is employed, to hold the printing-form rigidly in place when in printing position and to prevent the printing-form from giving way in such position either in the direction of the axis of the printing-form or in any direction transverse to the axis. In the embodiment of my device shown in Figs. 1 to 5 I have shown means for preventing such giving. Any suitable means may be employed for this purpose; but I prefer to use for this purpose the device shown in said figures, which will now be described. These means consist of stops, against which the frame is adapted to bear. The stops consist of a part 20 of the framework of the press, which act both as guides and as stops to prevent the giving of the printing-form, as above set forth. These stops are shaped, preferably, as shown in Fig. 4, a part 21 of the frame 6 extending on both sides of the stops and the frame itself at both of its sides snugly fitting the face of the stops 20, as shown in Fig. 4. Bearing-arms 7 have grooves at each side, into which takes a guide 22 of frame 6. By the above means a giving of the printing-form or its bearing-arms in the direction of the axis of the printing-form or in a direction transverse to that axis is effectually prevented.

Where the printing-form is a hollow shell-like tube mounted upon an interior form-support or mandrel, as shown in the drawings, I preferably remove the printing-tube or its form-support in the following manner: In the end of shaft 2 of the printing-form I preferably arrange a cylindrical socket 23, into which a pin 24 of a receiving-shaft 25 is adapted to take to lock the shaft 2 of the printing-form to and in line with the separate receiving-shaft 25 when it is desired to remove the printing-form or mandrel or to insert another in its place. The separate receiving-shaft 25 may be mounted and arranged in any suitable way. As this mounting and arrangement form no part of my invention, they are not shown in detail and will not be further described. In practice shaft 25 is brought in line with the end of shaft 2 of the printing-tube when it is desired to remove the latter from the press, pin 24 of the receiving-shaft is slipped into socket 23 of the shaft 2 of the printing-form, bearing-arms 7 are then separated, (the end of the printing-form and its mandrel being supported by the receiving-shaft,) and the printing-tube or the printing-tube and its mandrel are then slid laterally out of their working position in the press along receiving-shaft 25. Shaft 25 and

shaft 2 are then disconnected, and the receiving-shaft and its printing-tube are removed. When it is desired to insert a printing-tube or mandrel, or both, into the press, the same 5 operation reversed takes place.

Where the printing-form is not a shell mounted upon a supporting-axis, mandrel, or form-support, but is, for example, a solid cylinder, the receiving-shaft will not then, of 10 course, be used. In that case the printing-form will be slid out laterally by any suitable 15 means, as by hand.

In Fig. 6 I have shown my improved support in its preferred form mounted in a six-color lithographic press. In this press, 26 is the paper web on which the impressions are 20 made. 27 represents the ink-distributing rollers and their connecting mechanism, and 25 28 the frame of the press. Any suitable damping mechanism may be employed.

My improved device is especially valuable 30 in a multicolor lithographic press, as it enables the inking mechanism and the damping mechanism to be placed at any point upon 35 the periphery of the printing-forms, and these 40 can be arranged in any suitable manner and may occupy as much external space around 45 the printing-forms as may be desired, inasmuch as the insertion or removal of the printing-forms does not at all interfere with the 50 surrounding damping and inking mechanisms of the printing-forms.

In Figs. 7 to 11, inclusive, I have shown a 55 modification of my improved support for printing-forms. In this case the bearing-arms 77 instead of being movable directly toward or away from each other are pivoted at one end, as at 29, in a slide 30, moving in 60 guides 31 in the framework of the press, and are adapted to be moved apart by swinging upon said pivot away from one another. When they are swung together, they support 65 shaft 2 of the printing-form in the same manner as above described in reference to the device shown in Fig. 1. The printing-form is moved into and out of printing position and the pressure is regulated through pressure-bar 10, mounted on eccentric 32. This eccentric can be rotated by any suitable means.

50 When bearing-arms 77 in the form shown in Fig. 7 are brought together to support the printing-form, they are locked in their supporting position and are held from springing in the line of the axis of the printing-form or 55 transversely thereto by means of a swinging stop 33. This stop is mounted upon a short shaft 34, which is rotated from hand-wheel 35 through shaft 36, worm 37, and worm-wheel 38 upon shaft 34. Stop 33 has at its middle 60 portion, at one side, a recess 39, which extends part way through the stop. This recess fits over the ends of bearing-arms 77 when they are brought together and when the stop is rotated downward into the position shown in 65 Fig. 7. Preferably the sides and the ends of bearing-arms 77 are beveled, as shown in Figs. 9 and 11, and in that case the corre-

sponding sides of recess 39 in stop 33 are similarly beveled. The object of the bevel is to furnish a close and exact fit when stop 33 is 70 turned down over the ends of bearing-arms 77. In Fig. 11 the stop is shown in its open position and in Fig. 7 in its closed or locking position. When in its locking position, stop 33 holds bearing-arms 77 in their supporting 75 position and also effectually prevents any tendency of the bearing-arms of the printing-form to spring either in the line of the axis of the printing-form or transversely thereto.

In Figs. 12 and 13 I have shown still another modification of my improved support. In this case I connect to the outer end of pressure-bar 10 a hinged piece 40, hinged in the forks 41 of pressure-bar 10. The upper end of piece 40 is adapted to take into an opening 42 of box 43, carrying one end of the shaft of the printing-form. The outer end of piece 40 is screw-threaded and is provided with nuts 44 for purposes of adjustment and for securing piece 40 to the lips 45 of box 43. 90 When it is desired to remove or insert a printing-tube, upper nut 44 is unscrewed slightly, piece 40 is swung downward out of the way of the printing-tube, and the latter is removed or inserted laterally directly into or out of 95 working position in the press in the manner already described. Pressure-bar 10 and piece 40 thus constitute means both for supporting the printing-form and for controlling the pressure between it and the impression-surface, such means having a removable portion—namely, the piece 40—to permit of the insertion or removal of the printing-form directly into or out of working position in the 100 press.

In order to prevent giving of the printing-form in a horizontal direction, in the device shown in Figs. 12 and 13 I provide side stops 46 46, which, as shown, consist of arms having their inner ends 47 adapted to bear against 110 surfaces 48 of box 43. Arms 46 at their other end are provided with a loop 49, encircling eccentrics 50. By turning eccentrics 50, as by handle 51, bars 46 can be moved toward or away from surfaces 48. When the printing-form is in working position in the press, arms 46 are moved inward until their ends bear against surfaces 48, thus rigidly holding the printing-form from springing horizontally. Surfaces 48 are made of sufficient 115 width to permit of the movement of the printing-form from printing position to its position of rest without interfering with the contact of the faces 46 and 48 together.

Where printing-forms are used removable 125 from and replaceable upon their mandrels or shafts, I preferably use pre-established guides, with reference to which the printing-form may be seated on the mandrel or shaft in accurate predetermined position both longitudinally and transversely, and where printing-forms are used in a multicolor-press I preferably use guiding means with reference to which the printing-forms may be brought in 130

accurate predetermined relationship with the coöperating parts of the press for the purpose of register. The preëstablished guides for seating the tubular printing-forms upon their mandrels in the form of device shown in Figs. 1 to 5 consist of a rib 52 at one end of the mandrel 5, against which the tubular printing-surface 3 is made to snugly fit to seat the same in accurate predetermined position longitudinally on the shaft or mandrel, and a rib 53, projecting inward in the tubular printing-shell, adapted to take into a corresponding recess in mandrel 4 to seat the tube in accurate predetermined position on the form-support and shaft transversely or circumferentially. Where cylindrical printing-forms are employed, this transverse adjustment is also a circumferential one. The guiding means for bringing the different printing-forms in a multicolor-press into accurate predetermined relationship with the coöperating parts of the press consist, as shown, of a marked tooth 54 on a gear-wheel 55, keyed to shaft 2. By means of such marked tooth the different printing-forms of a multicolor-press may be brought into accurate predetermined relationship with the coöperating parts of the press for the purpose of register. Other suitable guiding means than those shown may be employed.

When my improved printing-forms are used in a multicolor-press, the printing-forms are made, preferably, of a predetermined size and shape, so as to properly coöperate with one another in obtaining register for the purpose of making them interchangeable, removable, and replaceable in the same or in different positions in the press.

By making the movable portion of the support a permanent part of the support or permanently secured thereto it can be moved out of its supporting position for the insertion or removal of a printing-form and can then be moved back again into its exact and accurately-predetermined supporting position without empiric adjustment, so that the printing-forms are always supported in exact and accurately-predetermined positions in the press without individual or empiric adjustment.

The term "printing-forms" as used in the specification and claims herein is not limited to forms with printing-surfaces, but is used to include not only such forms, but also forms with surfaces adapted to be transformed into printing-surfaces and forms to which printing-surfaces of any suitable kind and character are applied in any way or are adapted to be applied. The shape and form of the printing-form or of its printing-surface may be varied to suit the requirements of the particular case. Many modifications in other respects in the devices shown in the drawings may be made without departing from my invention and many of the parts shown herein may be omitted or other parts substituted therefor without departing from my inven-

tion, the essentials of which are set forth in the claims herein.

The removal and insertion of the printing-forms from or into their working positions in the press are by means of my invention done directly and easily and without interfering in any way with the arrangement of the inking mechanism or the dampening mechanism, if any, surrounding or exterior to the printing-forms and without any dismantling of the press, exact and accurate register of the printing-forms in a multicolor-press is obtained at once and without experiment or empiric adjustment, the construction of the press, especially of a multicolor-press, is greatly simplified and the mechanism is made more efficient, is more easily and effectively arranged, is easier of access, and better control of the same is obtained, and all giving of the printing-forms either in line with the axis of the printing-forms or in any direction transverse thereto is effectually prevented. My improved devices, moreover, do not interfere in any way with obtaining or regulating pressure between the printing-forms and the impression-surface.

What I claim as new, and desire to secure by Letters Patent, is—

1. In a press a support for a printing-form or its mandrel having a portion permanently secured to the said support but movable thereon so as to be removable from the path of the printing-form or its mandrel, when the latter is removed laterally from the press or is inserted from the side of the press into working position therein, to permit the printing-form or its mandrel or both to be inserted laterally into working position in the press or to be removed laterally therefrom without dismantling the press.

2. In a press the combination of a printing-form, an impression-surface, a support for a printing-form having a portion permanently secured to the said support but movable thereon so as to be removable from the path of the printing-form, when the latter is removed laterally from the press or is inserted from the side of the press into working position therein, to permit the printing-form to be inserted laterally into working position in the press or to be removed laterally therefrom without dismantling the press, and means for exerting pressure between the printing-form and the impression-surface.

3. In a press the combination of a printing-form, an impression-surface, and means for supporting the printing-form and for controlling the pressure between it and the impression-surface, a portion of said supporting or pressure means being permanently secured to the said support but movable thereon so as to be removable from the path of the printing-form, when the latter is removed laterally from the press or is inserted from the side of the press into working position therein, to permit the printing-form to be inserted laterally into working position in the press or to

be removed laterally therefrom without dismantling the press.

4. In a press the combination of a printing-form, an impression-surface, and means both for supporting the printing-form and for controlling the pressure between it and the impression-surface, a portion of said supporting and pressure means being permanently secured to the said support but movable thereon so as to be removable from the path of the printing-form, when the latter is removed laterally from the press or is inserted from the side of the press into working position therein, to permit the printing-form to be inserted laterally into working position in the press or to be removed laterally therefrom without dismantling the press.

5. In a press a support for a printing-form or its mandrel having a portion permanently secured to the said support but movable thereon so as to be removable from the path of the printing-form or mandrel, when the latter is removed laterally from the press or is inserted from the side of the press into working position therein, to permit the printing-form or mandrel or both to be inserted laterally into working position in the press or to be removed laterally therefrom without dismantling the press, and means for locking the support in its supporting position.

6. In a press a support for a printing-form or its mandrel having a portion removable from the path of the printing-form or mandrel, when the latter is removed laterally from the press or is inserted from the side of the press into working position therein, to permit the printing-form or mandrel to be inserted laterally into working position in the press or to be removed laterally therefrom, and means for holding the printing-form rigidly in place when in printing position for preventing the giving of the form while in such position.

7. In a press a support for a printing-form or its mandrel having a portion removable from the path of the printing-form or mandrel, when the latter is removed laterally from the press or is inserted from the side of the press into working position therein, to permit the printing-form or mandrel to be inserted laterally into working position in the press or to be removed laterally therefrom, and means for holding the printing-form rigidly in place when in printing position for preventing the giving of the form while in such position in the direction of the axis of the printing-form.

8. In a press a support for a printing-form having a portion removable from the path of the printing-form, when the latter is removed laterally from the press or is inserted from the side of the press into working position therein, to permit the printing-form to be inserted laterally into working position in the press or to be removed laterally therefrom, and means for holding the printing-form rigidly in place when in printing position for preventing the giving of the form

while in such position in a direction transverse to the axis of the printing-form.

9. In a press a support for a printing-form having a portion removable from the path of the printing-form, when the latter is removed laterally from the press or is inserted from the side of the press into working position therein, to permit the printing-form to be inserted laterally into working position in the press or to be removed laterally therefrom, and a stop, for holding the printing-form rigidly in place when in printing position for preventing the giving of the form while in such position in the direction of the axis of the printing-form.

10. In a press a support for a printing-form having a portion removable from the path of the printing-form, when the latter is removed laterally from the press or is inserted from the side of the press into working position therein, to permit the printing-form to be inserted laterally into working position in the press or to be removed laterally therefrom, and a stop, for holding the printing-form rigidly in place when in printing position for preventing the giving of the form while in such position in a direction transverse to the axis of the printing-form.

11. In a press a frame for carrying a printing-form or mandrel having two bearing-arms adapted to move toward or away from each other and adapted, when brought together to form a bearing for the shaft of the printing-form or mandrel, and, when separated, to permit the lateral removal or insertion of the printing-form or mandrel from or into the press, and means for moving said arms toward or away from each other.

12. In a press the combination of an impression-surface, a printing-form, a frame for carrying the printing-form having two bearing-arms adapted to move toward or away from each other and adapted, when brought together, to form a bearing for the shaft of the printing-form, and, when separated, to permit the lateral removal or insertion of the printing-form from or into the press, means for moving said arms toward or away from each other and means for moving the frame to move the printing-form into or out of printing position and to regulate the pressure.

13. In a press a frame for carrying a printing-form or mandrel having two bearing-arms adapted to move toward or away from each other and adapted, when brought together, to form a bearing for the shaft of the printing-form or mandrel, and, when separated, to permit the lateral removal or insertion of the printing-form or mandrel from or into the press, means for moving said arms toward or away from each other, and means for locking the bearing-arms in their supporting position.

14. In a press the combination of an impression-surface, a printing-form, a frame for carrying the printing-form having two bearing-arms adapted to move toward or away

from each other and adapted, when brought together, to form a bearing for the shaft of the printing-form, and, when separated, to permit the lateral removal or insertion of the printing-form from or into the press, means for moving said arms toward or away from each other, means for locking the bearing-arms in their supporting position, and means for moving the frame to move the printing-form into or out of printing position and to regulate the pressure.

15. In a press a frame for carrying a printing-form or mandrel having two bearing-arms adapted to move toward or away from each other and adapted, when brought together, to form a bearing for the shaft of the printing-form or mandrel, and, when separated, to permit the lateral removal or insertion of the printing-form or mandrel from or into the press, means for moving said arms toward or away from each other and means for holding the printing-form rigidly in place when in printing position for preventing the giving of the form while in such position.

25. 16. In a press the combination of an impression-surface, a printing-form, a frame for carrying the printing-form having two bearing-arms adapted to move toward or away from each other and adapted, when brought together, to form a bearing for the shaft of the printing-form, and, when separated, to permit the lateral removal or insertion of the printing-form from or into the press, means for moving said arms toward or away from each other, means for locking the bearing-arms in their supporting position, a stop, upon which the frame is adapted to slide and with which it engages, to hold the printing-form rigidly in place when in printing position for preventing the giving of the form while in such position in a direction parallel with the axis of the printing-form or transverse thereto, and means for moving the frame along the stop to move the printing-form into or out of printing position and to regulate the pressure.

17. In a press a frame for carrying a printing-form having two bearing-arms adapted to move toward or away from each other and adapted, when brought together, to form a bearing for the shaft of the printing-form and, when separated to permit the lateral removal or insertion of the printing-form from or into the press, two rods oppositely screw-threaded at their opposite ends, nuts connected with the bearing-arms and engaging with said rods, the nuts of one arm engaging with one set of the screw-threaded ends of said rods and the nuts of the other arm engaging with the oppositely-screw-threaded ends of said rods and means for rotating the said rods to move the said arms toward or away from each other.

18. In a press a frame for carrying a printing-form having two bearing-arms adapted to move toward or away from each other and

adapted, when brought together, to form a bearing for the shaft of the printing-form and, when separated, to permit the lateral removal or insertion of the printing-form from or into the press, two rods oppositely screw-threaded at their opposite ends, nuts connected with the bearing-arms and engaging with said rods, the nuts of one arm engaging with one set of the screw-threaded ends of said rods and the nuts of the other arm engaging with the oppositely-screw-threaded ends of said rods and means for rotating the said rods to move the said arms toward or away from each other, said means including a worm and worm-wheel, whereby the said arms will be locked in their supporting position.

19. In a press a frame for carrying a printing-form having two bearing-arms adapted to move toward or away from each other and adapted, when brought together, to form a bearing for the shaft of the printing-form and, when separated, to permit the lateral removal or insertion of the printing-form from or into the press, two rods oppositely screw-threaded at their opposite ends, nuts connected with the bearing-arms and engaging with said rods, the nuts of one arm engaging with one set of the screw-threaded ends of said rods and the nuts of the other arm engaging with the oppositely-screw-threaded ends of said rods, a gear upon each of said rods, a common gear-wheel arranged between the said gear-wheels mounted upon the rods and meshing therewith, and means for driving said common gear-wheel, the said means including a worm and worm-wheel, whereby the two bearing-arms may be moved toward or away from each other and the said arms will be locked in their supporting position.

20. In a press a frame for carrying a printing-form having two bearing-arms adapted to move toward or away from each other and adapted, when brought together, to form a bearing for the shaft of the printing-form and, when separated, to permit the lateral removal or insertion of the printing-form from or into the press, two rods oppositely screw-threaded at their opposite ends, nuts connected with the bearing-arms and engaging with said rods, the nuts of one arm engaging with one set of the screw-threaded ends of said rods and the nuts of the other arm engaging with the oppositely-screw-threaded ends of said rods, a gear on each rod, a common gear-wheel mounted upon the framework of the press between the said two gear-wheels and adapted to mesh with each, said common gear-wheel having its teeth wide enough to permit the movement of the gears, as the frame moves to carry the printing-form into or out of printing position, without interfering with the meshing of the said gear-wheels with one another, means mounted upon the framework of the press for driving said common gear-wheel, the said means including a worm and worm-wheel, whereby the two bear-

ing-arms may be moved toward or away from each other and the said arms will be locked in their supporting position and the frame may be moved without interfering with the means for moving the bearing-arms.

21. In a press a frame for carrying a printing-form having two bearing-arms adapted to move toward or away from each other and adapted, when brought together, to form a bearing for the shaft of the printing-form and, when separated, to permit the lateral removal or insertion of the printing-form from or into the press, two rods oppositely screw-threaded at their opposite ends, nuts connected with the bearing-arms and engaging with said rods, the nuts of one arm engaging with one set of the screw-threaded ends of said rods and the nuts of the other arm engaging with the oppositely-screw-threaded ends of said rods, a gear on each rod, a common gear-wheel mounted upon the framework of the press between the said two gear-wheels and adapted to mesh with each, said common gear-wheel having its teeth wide enough to permit the movement of the gears, as the frame moves to carry the printing-form into or out of printing position, without interfering with the meshing of the said gear-wheels with one another, means mounted upon the framework of the press for driving said common gear-wheel, the said means including a worm and worm-wheel, whereby the two bearing-arms may be moved toward or away from each other and the said arms will be locked in their supporting position and the frame may be moved without interfering with the means for moving the bearing-arms, a stop, upon which the frame is adapted to slide and with which it engages, to hold the printing-form rigidly in place when in printing position for preventing the giving of the form while in such position in a direction parallel with the axis of the printing-form or transverse thereto, and means for moving the frame along the stop to move the printing-form into or out of printing position and to regulate the pressure.

22. In a press a support for a curved printing-form having a portion permanently secured to the said support but movable thereon so as to be removable from the path of the printing-form, when the latter is removed laterally from the press or is inserted from the side of the press into working position therein, to permit the printing-form to be inserted laterally into working position in the press or to be removed laterally therefrom without dismantling the press.

23. In a press the combination of a curved printing-form, an impression-surface, a support for a printing-form having a portion permanently secured to the said support but movable thereon so as to be removable from the path of the printing-form, when the latter is removed laterally from the press or is inserted from the side of the press into working position therein, to permit the printing-form to be inserted laterally into working position in the

press or to be removed laterally therefrom without dismantling the press, and means for exerting pressure between the printing-form and the impression-surface.

24. In a press a support for a curved printing-form having a portion permanently secured to the said support but movable thereon so as to be removable from the path of the printing-form, when the latter is removed laterally from the press or is inserted from the side of the press into working position therein, to permit the printing-form to be inserted laterally into working position in the press or to be removed laterally therefrom without dismantling the press, and means for locking the support in its supporting position.

25. In a press a support for a curved printing-form having a portion removable from the path of the printing-form, when the latter is removed laterally from the press or is inserted from the side of the press into working position therein, to permit the printing-form to be inserted laterally into working position in the press or to be removed laterally therefrom, and means for holding the printing-form rigidly in place when in printing position for preventing the giving of the form while in such position.

26. In a press the combination of an impression-surface, a curved printing-form, a frame for carrying the printing-form having two bearing-arms adapted to move toward or away from each other and adapted, when brought together, to form a bearing for the shaft of the printing-form and, when separated, to permit the lateral removal or insertion of the printing-form from or into the press, means for moving said arms toward or away from each other, means for locking the bearing-arms in their supporting position, and means for moving the frame to move the printing-form into or out of printing position and to regulate the pressure.

27. In a press a support for a printing-cylinder having a portion permanently secured to the said support but movable thereon so as to be removable from the path of the printing-cylinder, when the latter is removed laterally from the press or is inserted from the side of the press into working position therein, to permit the printing-cylinder to be inserted laterally into working position in the press or to be removed laterally therefrom without dismantling the press.

28. In a press the combination of a printing-cylinder, an impression-surface, a support for a printing-cylinder having a portion permanently secured to the said support but movable thereon so as to be removable from the path of the printing-cylinder, when the latter is removed laterally from the press or is inserted from the side of the press into working position therein, to permit the printing-cylinder to be inserted laterally into working position in the press or to be removed laterally therefrom without dismantling the press, and means for exerting pressure between

the printing-cylinder and the impression-surface.

29. In a press a support for a printing-cylinder having a portion permanently secured to the said support but movable thereon so as to be removable from the path of the printing-cylinder, when the latter is removed laterally from the press or is inserted from the side of the press into working position therein, to permit the printing-cylinder to be inserted laterally into working position in the press or to be removed laterally therefrom without dismantling the press, and means for locking the support in its supporting position.

15 30. In a press a support for a printing-cylinder having a portion removable from the path of the printing-cylinder, when the latter is removed laterally from the press or is inserted from the side of the press into working position therein, to permit the printing-cylinder to be inserted laterally into working position in the press or to be removed laterally therefrom, and means for holding the printing-cylinder rigidly in place when in printing position for preventing the giving of the cylinder while in such position.

31. In a press the combination with a tubular printing-form and a mandrel therefor, the tubular printing-form being removable from and replaceable on the mandrel, of a support for the mandrel and tubular printing-form having a portion permanently secured to the said support but movable thereon so as to be removable from the path of the tubular printing-form, when the latter is removed laterally off from the mandrel in the press or is inserted from the side of the press onto the mandrel and into working position in the press, to permit the tubular printing-form to be inserted laterally into working position in the press or to be removed laterally therefrom without dismantling the press.

32. In a press the combination with a tubular printing-form and a mandrel therefor, the tubular printing-form being removable from and replaceable on the mandrel, of a support for the mandrel and tubular printing-form having a portion removable from the path of the tubular printing-form, when the latter is removed laterally off from the mandrel in the press or is inserted from the side of the press onto the mandrel and into working position in the press, to permit the tubular printing-form to be inserted laterally into working position in the press or to be removed laterally therefrom, means for locking the support in its supporting position and means for holding the printing-form rigidly in place when in printing position for preventing the giving of the form while in such position.

33. In a press the combination of a shaft, a hollow mandrel adapted to fit thereon and removable therefrom and replaceable thereon, a hollow tubular printing-form adapted to fit upon the mandrel in the press and removable therefrom and replaceable thereon, and a sup-

port for the shaft, mandrel and tubular printing-form having a portion permanently secured to the said support but movable thereon so as to be removable from the path of the tubular printing-form or the hollow mandrel when the form or the mandrel or both are removed laterally from the press or are inserted from the side of the press into working position therein, to permit the printing-form to be inserted laterally into working position in the press or to be removed laterally therefrom without dismantling the press.

34. In a press the combination of a shaft, a hollow mandrel adapted to fit thereon and removable therefrom and replaceable thereon, a hollow tubular printing-form adapted to fit upon the mandrel in the press and removable therefrom and replaceable thereon, and a support for the shaft, mandrel and tubular printing-form having a portion removable from the path of the tubular printing-form or the hollow mandrel when the form or the mandrel or both are removed laterally from the press or are inserted from the side of the press into working position therein, to permit the printing-form to be inserted laterally into working position in the press or to be removed laterally therefrom, means for locking the support in its supporting position and means for holding the printing-form rigidly in place when in printing position for preventing the giving of the form while in such position.

35. In a multicolor-press the combination of a series of printing-forms, a support for each printing-form, having a portion permanently secured to the said support but movable thereon so as to be removable from the path of the said printing-form, when it is removed laterally from the press or is inserted from the side of the press into working position therein, to permit the printing-forms to be inserted laterally into working position in the press or to be removed laterally therefrom without dismantling the press.

36. In a multicolor-press the combination of a series of printing-forms, a support for each printing-form, having a portion permanently secured to the said support but movable thereon so as to be removable from the path of the said printing-form, when it is removed laterally from the press or is inserted from the side of the press into working position therein, to permit the printing-forms to be inserted laterally into working position in the press or to be removed laterally therefrom without dismantling the press and means for locking each support in its supporting position.

37. In a multicolor-press the combination of a series of printing-forms, a support for each printing-form, having a portion removable from the path of the said printing-form, when it is removed laterally from the press or is inserted from the side of the press into working position therein, to permit the printing-forms to be inserted laterally into working position in the press or to be removed later-

ally therefrom, and means for holding the printing-form rigidly in place when in printing position for preventing the giving of the form while in such position.

5 38. In a multicolor-press the combination of suitable impression-surface, a series of printing-forms, a frame for carrying each printing-form having two bearing-arms adapted to move toward or away from each other and adapted, when brought together to form a bearing for the shaft of the said printing-form and, when separated, to permit the lateral removal or insertion of the said printing-form from or into the press, means for moving said arms toward or away from each other, means for locking the bearing-arms in their supporting positions, and means for moving each frame to move its corresponding printing-form into or out of printing position 20 and to regulate the pressure between the said printing-form and its impression-surface.

39. In a multicolor-printing press the combination of an impression-drum, a series of printing-forms arranged circumferentially around the drum, a support for each printing-form having a portion permanently secured to the said support but movable thereon so as to be removable from the path of the said printing-form, when it is removed laterally from the press or is inserted from the side of the press into working position therein, to permit the printing-forms to be inserted laterally into working position in the press or to be removed laterally therefrom without dismantling the press, and means for exerting pressure between the printing-forms and the impression-drum.

40. In a multicolor-printing press the combination of an impression-drum, a series of printing-forms arranged circumferentially around the drum, a support for each printing-form having a portion permanently secured to the said support but movable thereon so as to be removable from the path of the said printing-form, when it is removed laterally from the press or is inserted from the side of the press into working position therein, to permit the printing-forms to be inserted laterally into working position in the press or to be removed laterally therefrom without dismantling the press, means for locking each support in its supporting position, and means for exerting pressure between the printing-forms and the impression-drum.

55 41. In a multicolor-printing press the combination of an impression-drum, a series of printing-forms arranged circumferentially around the drum, a support for each printing-form having a portion removable from the path of the said printing-form, when it is removed laterally from the press or is inserted from the side of the press into working position therein, to permit the printing-forms to be inserted laterally into working position in the press or to be removed laterally therefrom, means for holding the printing-forms

rigidly in place when in printing position for preventing the giving of the forms while in such position and means for exerting pressure between the printing-forms and the impression-drum. 70

42. In a multicolor-press the combination of an impression-drum, a series of printing-forms arranged circumferentially around the drum, a frame for carrying each printing-form having two bearing-arms adapted to move toward or away from each other and adapted, when brought together, to form a bearing for the shaft of the said printing-form and, when separated, to permit the lateral removal or insertion of said printing-form from or into the press, means for moving said arms toward or away from each other, means for locking the bearing-arms in their supporting positions, and means for moving the frames to move the printing-forms into or out of printing position and to regulate the pressure between the printing-forms and the impression-drum. 80 85

43. In a multicolor-press the combination of a series of tubular printing-forms, a mandrel for each printing-form, the tubular printing-forms being removable from and replaceable upon the mandrels, and a support for each mandrel and tubular printing-form having a portion permanently secured to the said support but movable thereon so as to be removable from the path of the tubular printing-form, when the latter is removed laterally off from the mandrel in the press or is inserted from the side of the press directly onto the mandrel and into working position in the press, to permit the tubular printing-forms to be inserted laterally directly into working position in the press or to be removed laterally directly therefrom without dismantling the press. 90 95 100

44. In a multicolor-press the combination of a series of tubular printing-forms, a mandrel for each printing-form, the tubular printing-forms being removable from and replaceable upon the mandrels, and a support for each mandrel and tubular printing-form having a portion permanently secured to the said support but movable thereon so as to be removable from the path of the printing-form, when the latter is removed laterally off from the mandrel in the press or is inserted from the side of the press directly onto the mandrel and into working position in the press, to permit the tubular printing-forms to be inserted laterally directly into working position in the press or to be removed laterally directly therefrom without dismantling the press, and means for locking each support in its supporting position. 110 115 120 125

45. In a multicolor-press the combination of a series of tubular printing-forms, a mandrel for each printing-form, the tubular printing-forms being removable from and replaceable upon the mandrels, and a support for each mandrel and tubular printing-form hav-

ing a portion removable from the path of the tubular printing-form, when the latter is removed laterally off from the mandrel in the press or is inserted from the side of the press 5 directly onto the mandrel and into working position in the press, to permit the tubular printing-forms to be inserted laterally directly into working position in the press or to be removed laterally directly therefrom and means 10 for holding the printing-forms rigidly in place when in printing position for preventing the giving of the forms while in such position.

46. In a multicolor-press the combination of an impression-drum, a series of tubular printing-forms arranged circumferentially around the drum, a mandrel for each printing-form, the tubular printing-forms being removable from and replaceable upon the mandrels, a frame for carrying each printing-form 15 having two bearing-arms adapted to move toward or away from each other and adapted, when brought together to form a bearing for the shaft of the said printing-form and, when separated, to permit the lateral removal or 20 insertion of the said printing-form from or into the press, means for moving said arms toward or away from each other, means for locking the bearing-arms in their supporting positions, and means for moving each frame 25 to move its corresponding printing-form into or out of printing position and to regulate the pressure between the said printing-form and the impression-drum.

47. In a multicolor-press the combination 30 of an impression-drum, a series of tubular printing-forms arranged circumferentially around the drum, a mandrel for each printing-form, the tubular printing-forms being removable from and replaceable upon the 35 mandrels, a support for each mandrel and tubular printing-form having a portion permanently secured to the said support but movable thereon so as to be removable from the path of the tubular printing-form, when the 40 latter is removed laterally off from the mandrel in the press or is inserted from the side of the press laterally and directly onto the mandrel and into working position in the 45 press, to permit the printing-forms to be inserted laterally directly into working position in the press or to be removed laterally directly therefrom without dismantling the press, and means for exerting pressure between the printing-forms and the impression-drum.

48. In a multicolor-press the combination 50 of an impression-drum, a series of tubular printing-forms arranged circumferentially around the drum, a mandrel for each printing-form, the tubular printing-forms being removable from and replaceable upon the 55 mandrels, a support for each mandrel and tubular printing-form having a portion permanently secured to the said support but movable thereon so as to be removable from the path of the tubular printing-form, when the latter is removed laterally off from the man-

drel in the press or is inserted from the side of the press directly onto the mandrel and into working position in the press, to permit 70 the tubular printing-forms to be inserted laterally directly into working position in the press or to be removed laterally directly therefrom without dismantling the press, means for locking each support in its supporting position, and means for exerting pressure between the printing-forms and the impression-drum.

49. In a multicolor-press the combination of an impression-drum, a series of tubular 80 printing-forms arranged circumferentially around the drum, a mandrel for each printing-form, the tubular printing-forms being removable from and replaceable upon the mandrels, a support for each mandrel and tubular printing-form having a portion permanently secured to the said support but movable thereon so as to be removable from the path of the tubular printing-form, when the latter is removed laterally off from the mandrel in the press or is inserted from the side of the press directly onto the mandrel and into working position in the press, to permit 85 the tubular printing-forms to be inserted laterally directly into working position in the press or to be removed directly therefrom without dismantling the press, means for preventing the springing or giving of the printing-forms when in printing position and means for exerting pressure between the 90 printing-forms and the impression-drum.

50. In a multicolor-press the combination of an impression-surface, a series of printing-forms, a support for each printing-form having a portion removable from the path of the 105 said printing-form, when it is removed laterally from the press or is inserted from the side of the press into working position therein, to permit the printing-forms to be inserted laterally into working position in the press or to be removed laterally therefrom, and pre-established guides by means of which the 110 printing-form may be seated in the press in accurate predetermined position both longitudinally and transversely and may be brought 115 into accurate relationship with coöperating parts of the press for the purpose of register.

51. In a multicolor-press the combination of an impression-surface, a series of printing-forms, a support for each printing-form having a portion removable from the path of the 120 said printing-form, when it is removed laterally from the press or is inserted from the side of the press into working position therein, to permit the printing-forms to be inserted 125 laterally into working position in the press or to be removed therefrom, and means for holding the printing-forms rigidly in place when in printing position for preventing the giving of the forms while in such position, and pre-established guides by means of which the 130 printing-forms may be seated in the press in accurate predetermined position both longitudinally and transversely and may be brought

into accurate relationship with coöperating parts of the press for the purpose of register.

52. In a multicolor-press the combination of an impression-surface, a series of printing-forms, a support for each printing-form, a frame for carrying each printing-form having two bearing-arms adapted to move toward or away from each other and adapted, when brought together to form a bearing for the shaft of the said printing-form and, when separated, to permit the lateral removal or insertion of the said printing-form from or into the press, means for moving said arms toward or away from each other, means for locking the bearing-arms in their supporting positions, and means for moving each frame to move its corresponding printing-form into or out of printing position and to regulate the pressure between the said printing-form and its impression - surface, and preëstablished guides by means of which the printing-forms may be seated in the press in accurate predetermined position both longitudinally and transversely and may be brought into accurate relationship with coöperating parts of the press for the purpose of register.

53. In a multicolor-press the combination of an impression-drum, a series of printing-forms arranged circumferentially around the drum, a support for each printing-form having a portion removable from the path of the said printing-form, when it is removed laterally from the press or is inserted from the side of the press into working position therein, to permit the printing-forms to be inserted laterally into working position in the press or to be removed laterally therefrom, and means for exerting pressure between the printing-forms and the impression-drum and preëstablished guides by means of which the printing-forms may be seated in the press in accurate predetermined position both longitudinally and transversely and may be brought into accurate relationship with coöperating parts of the press for the purpose of register.

54. In a multicolor-printing press the combination of an impression-drum, a series of printing - forms arranged circumferentially around the drum, a support for each printing-form having a portion removable from the path of the said printing-form, when it is removed laterally from the press or is inserted from the side of the press into working position therein, to permit the printing-forms to be inserted laterally into working position in the press or to be removed laterally therefrom, means for locking each support in its supporting position, and means for exerting pressure between the printing-forms and the impression-drum and preëstablished guides by means of which the printing-forms may be seated in the press in accurate predetermined position both longitudinally and transversely and may be brought into accurate relationship with coöperating parts of the press for the purpose of register.

55. In a multicolor-printing press the combination of an impression-drum, a series of printing - forms arranged circumferentially around the drum, a support for each printing-form having a portion removable from the path of the said printing-form, when it is removed laterally from the press or is inserted from the side of the press into working position therein, to permit the printing-forms to be inserted laterally into working position in the press or to be removed laterally therefrom, means for holding the printing-forms rigidly in place when in printing position for preventing the giving of the forms while in such position and means for exerting pressure between the printing-forms and the impression-drum and preëstablished guides by means of which the printing-forms may be seated in the press in accurate predetermined position both longitudinally and transversely and may be brought into accurate relationship with coöperating parts of the press for the purpose of register.

56. In a multicolor-press the combination of an impression-drum, a series of tubular printing - forms arranged circumferentially around the drum, a mandrel for each printing-form, the tubular printing-forms being removable from and replaceable upon the mandrels, preëstablished guides with reference to which the tubular printing-forms may be seated on their mandrels in accurate predetermined position both longitudinally and circumferentially, a support for each mandrel and tubular printing-form having a portion removable from the path of the tubular printing-form when the latter is removed laterally off from the mandrel in the press or is inserted from the side of the press laterally and directly onto the mandrel and into working position in the press, to permit the printing-forms to be inserted laterally directly into working position in the press or to be removed laterally directly therefrom, means for exerting pressure between the printing-forms and the impression-drum and guiding means with reference to which the tubular printing-forms may be brought into accurate predetermined relationship with the coöperating parts of the press for the purpose of register.

57. In a multicolor-press the combination of an impression-drum, a series of tubular printing - forms arranged circumferentially around the drum, a mandrel for each printing-form, the tubular printing-forms being removable from and replaceable upon the mandrels, preëstablished guides with reference to which the tubular printing-forms may be seated on their mandrels in accurate predetermined position both longitudinally and circumferentially, a support for each mandrel and tubular printing-form having a portion removable from the path of the tubular printing-form, when the latter is removed laterally off from the mandrel in the press or is inserted from the side of the press directly

onto the mandrel and into working position in the press, to permit the tubular printing-forms to be inserted laterally directly into working position in the press or to be removed laterally directly therefrom, means for locking each support in its supporting position, means for exerting pressure between the printing-forms and the impression-drum and guiding means with reference to which the tubular printing-forms may be brought into accurate predetermined relationship with the coöperating parts of the press for the purpose of register.

58. In a multicolor-press the combination 15 of an impression-drum, a series of tubular printing-forms arranged circumferentially around the drum, a mandrel for each printing-form, the tubular printing-forms being removable from and replaceable upon the 20 mandrels, preëstablished guides with reference to which the tubular printing-forms may be seated on their mandrels in accurate predetermined position both longitudinally and circumferentially, a support for each mandrel and tubular printing-form having a por-

tion removable from the path of the tubular printing-form, when the latter is removed laterally off from the mandrel in the press or is inserted from the side of the press directly onto the mandrel and into working position 30 in the press, to permit the tubular printing-forms to be inserted laterally directly into working position in the press or to be removed directly therefrom, means for holding the printing-forms rigidly in place when in 35 printing position for preventing the giving of the forms while in such position means for exerting pressure between the printing-forms and the impression-drum and guiding means with reference to which the tubular printing-forms may be brought into accurate predetermined relationship with the coöperating part 40 of the press for the purpose of register.

In testimony whereof I have signed my name to this specification in the presence of 45 two subscribing witnesses.

EDWARD HETT.
